UNITED STATES PATENT OFFICE.

THOMAS H. NUTE, OF EAST PROVIDENCE, RHODE ISLAND.

JACK-SPOOLER.

1,222,975.

Specification of Letters Patent. Patented Apr. 17, 1917.

Application filed July 8, 1915. Serial No. 38,799.

To all whom it may concern:

Be it known that I, THOMAS H. NUTE, a citizen of the United States, residing at East Providence, in the county of Providence, State of Rhode Island, have invented certain new and useful Improvements in Jack-Spoolers, of which the following is a specification.

My invention relates to jack-spoolers and consists of improvements in the traverse-mechanism therefor. The object of my improvement is to provide a simplified attachment universally applicable to practically all types of spoolers and adapted to be driven from a going part of the machine to operate the front and the back traverse at different speeds. My improved device consists essentially of a self-contained, coordinated mechanism which can be attached to any type of spooler without alteration or adjustment in the main elements of the machine, and which may be driven therefrom to effect a quick traverse of the front guide-bar and a relatively slow traverse of the rear bar.

The invention is fully described in the following specification, illustrated by the accompanying drawings, in which like reference characters designate like parts. In the drawings:

Figure 1 is an end elevation of a usual type of jack-spooler illustrating my improved traverse-mechanism applied thereto;

Fig. 2, an enlarged side view of the traverse-mechanism showing its relation to the front and rear traverse-bars of the spooler;

Fig. 3, an end view of the traverse-mechanism showing the connection between the front traverse-bar and its traverse-cam; and

Fig. 4, a detail view of the driving connections for the rear traverse-bar.

Referring first to Fig. 1, B designates the end frame of a conventional form of jack-spooler to which my attachment may be applied and it is to be understood that the invention is also adaptable to various other types of machines of this class. Journaled in bearings b at the front of the end-frames B of the machine is a longitudinal shaft d which supports and rotates the driving-drum D. The jack-spool S is mounted with its barrel s resting on the periphery of the drum D and is supported in position by means of its gudgeons s' which fit into slots c on the front of vertical guide-members C. The guides C are adapted to slide upwardly

on the side-frames B as the thread or yarn builds up on the barrel s of the spool S.

Projecting upwardly from the side-frames B are suitable arms b' formed at the top with bearings b² for the front traverse-bar F. The bar F is mounted to slide in the bearings b² and is provided with a plurality of guiding-eyes or notches f, f, etc., equally spaced along its length, see Fig. 3, 60 and adapted to receive the individual strands y of the yarn or thread to be traversed in relation to the spool S. At the rear of the traverse-bar F is a lease-rod or guiding-bar E mounted in a bearing b³ on the arm b' and under or over which the yarns y are led before they pass through the guide-notches f. At the rear of the machine the end-frames B are formed with upwardly projecting arms b⁴ provided with vertical 65 slots b⁵. Two tension-rolls T, T', having gudgeons t, t', journaled in the slots b⁵, are mounted one above the other with their peripheries in contact to press on the yarn y as it passes around and between their surfaces. At the rear of the tension-rolls T, T' 70 is the back-traverse-rod G provided with spaced guiding-eyes g and mounted to slide longitudinally in brackets b⁶ fastened to the arms b⁴. A lease-rod H is mounted at the 75 ends of the brackets b⁶ to serve as a guide for the yarns y as they pass through the guiding-eyes g in the traverse-rod G. All of the parts above described are of substantially the same arrangement as usually 80 provided in machines of this type.

My improved traverse-motion is applied to use in connection with this well-known mechanism of the jack-spooler as follows: To the side of the frame B, I attach a 95 bracket K into which is screwed a headed stud k adapted to serve as a bearing for a rotatable traverse-cam L. The cam L is of a usual type formed with a helical groove l on its periphery as shown most clearly in Fig. 3. Secured to or made integral with the cam L is a gear l' adapted to mesh with a similar gear J fast on the end of the drum-shaft d. Extending upwardly from the bracket K is an arm k' carrying a stud k² 100 on which is pivoted a rockable traverse-arm or lever M. At its lower end the lever M carries a stud m on which is journaled a roll m' engaging the groove l in the cam L. The upper arm of the lever M is formed 105 with a longitudinal slot m² through which it is connected to reciprocate the front trav-

erse-bar F. In order to render the traversing-mechanism interchangeably and universally attachable to all types of spoolers, I provide a novel form of adjustable means for connecting it with the traverse-bar as follows:

A clamp-member N formed with a rectangular slot n is adapted to slip onto the end of the traverse-bar F, and projecting from its side is a horizontal arm or rod n' . The clamp N is secured to the bar F by means of a set-screw n^2 to allow it to be adjusted in position longitudinally thereon and the arm n' is adapted to receive the hub o of an arm O formed with a slot o' . The hub o is secured to the arm n' of the clamp N by means of set-screws o^2 , o^2 which allow for lateral adjustment of the arm O to bring it into position adjacent the side of the traverse-lever M. The lever M is coupled to the arm O to impart reciprocating motion to the traverse-bar F through the means of a stud P adjustable in the slot o' . As shown in Fig. 2, the stud P passes through a collar p or bushing p fitted to the slot m^2 of the lever M and arranged with washers p' , p^2 on either side thereof. A thumb-nut p^3 is screwed onto the stud P against a washer p^4 to bind the latter and the washer p^2 against the arm O, while the bushing p is left free to slide in the slot m^2 of the lever M. If preferred, the stud P might be formed with an enlarged head adapted to fit the slot m^2 in the lever M and having its shoulder abutting the side of the arm O so that the washers could be dispensed with. By adjusting the stud P up or down in the slot o' the range of action of the lever M may be altered to vary the length of traverse imparted to the bar F by the cam L.

Secured to the side of the frame B are two brackets R and U formed with bearings for a horizontal shaft R', see Fig. 1. Usually the bracket R and shaft R' constitute standard elements of the machine as originally designed. Suitable collars r , r' on the shaft R' abut the ends of the bearing on the bracket R to hold the shaft from longitudinal movement, and at its forward end is keyed or otherwise secured a toothed gear V adapted to serve as a ratchet-wheel. Screwed into the lower end of the traverse-lever M on the opposite side from the rolls m' is a stud m^3 which serves as a bearing for a pawl V' arranged with its ends adapted to engage the teeth on the ratchet-wheel V. Referring to Fig. 3, the bracket U is formed with a cylindrical pocket u in which is slidably mounted a plug U' pressed outwardly by a helical spring u^2 . The end of the plug U' is flattened off at u^3 and beveled on its opposite side at u^4 to adapt it to engage the teeth on the ratchet-wheel V to act as an escapement or check-pawl for the latter. When the wheel V is turned in the

direction indicated by the arrow α , Fig. 3, through the action of the pawl V' oscillated on the lever M, the check-pawl U' will be forced back against the pressure of its spring u^2 from the action of the teeth on the wheel V riding across the bevel u^4 . On the other hand, the pressure of the spring u^2 maintains the pointed end of the pawl constantly in engagement with the teeth on the ratchet V to prevent backward rotation of the latter during the rearward movement of the actuating-pawl V'.

Secured to the shaft R' at the opposite end from the ratchet-wheel V is an eccentric-disk W which serves as a reciprocating-means for the rear traverse-bar G, see Fig. 4. At the end of the bar G, I attach a clamp-member W' similar in form to the front traverse-clamp N and provided with a depending arm w. The clamp-member W' is adjusted in position and secured in place on the bar G by means of a set-screw w' to adapt the arm w to bear against the periphery of the eccentric W. To maintain the arm w in operative relation to the eccentric W a cord or chain z is attached to it at z' and leads over a rod z^2 , or other suitable support on the machine-frame, with a weight Z suspended at its end.

Having now described the construction and arrangement of my improved mechanism in detail, the method of operation of the complete machine will next be explained: It is to be understood that in practically all spooling-machines of this type the main elements, such as the driving-drum, the spool-supports and traverse-bars, are of substantially the same construction and arrangement as here shown, except that they differ slightly in dimensions and detail of coördination. The eccentric-shaft R', as before mentioned, is also usually provided on the machine frame as an element of the back-traverse mechanism. My present improved attachment is applied to use in connection with these standard parts of the machine in such manner as to require a minimum of new elements and practically no alteration or rearrangement of the basic mechanism. The bracket K, the cam-gear L—L' which it supports, and the connected traverse-lever M with its pawl V' are the principal elements of my new mechanism, and together with the arm O, bracket U and clamps N and W' constitute practically all the parts necessary to be added to the main machine. These elements are attached in place without the necessity of any machining or fitting except in some instances where holes must be provided for the bracket bolts. In any event, however, my new attachment can be applied to the spooler with very little labor and at very slight expense. After the parts are fixed in position as hereinbefore described the mechanism functions as fol-

lows: The yarns y lead across the guide-rod H and through the thread-eyes g in the rear traverse-bar G , thence under and around the tension-roller T' , up under the pressure-roller T , whence they are then drawn across the machine to the lease-rod E . From the rod E they pass through the eyes or slots f in the front traverse-bar F and thence lead to the barrel of the spool S . When the machine is started the driving-drum D rotates the spool S through contact with its barrel s and the yarns y are thereby wound onto the barrel while the spool rises with the growth in diameter of the winding. Meanwhile, during the rotation of the spool, the gear J on the drum-shaft d drives the gear J' to rotate the cam L , and the latter imparts an oscillating motion to the traverse-lever M as the roll m' travels in the groove l . This rocking movement of the lever M is transmitted through the stud P to reciprocate the front traverse-bar F with a relatively quick movement, and the extent of traverse of the bar may be regulated as required by simply adjusting the stud P up or down in the slot o' . That is to say, the traverse of the bar F is adjusted in accordance with the number of strands or ends being wound onto the barrel s so that the yarn will completely fill the spool between its heads.

As the lever M oscillates under the action of the cam L the pawl V' at its lower end acts on the ratchet-wheel V to rotate the shaft R' . The rotation of the shaft R' turns the cam or eccentric W to cause it to act on the arm w of the clamp W' to reciprocate the rear traverse-bar G with a slow motion. This slow traverse of the bar G acts to shift the yarns y back and forth along the tension-rolls T, T' , the object being to prevent them from wearing grooves in the surface of the rolls.

I am aware that it is not broadly new in the art to apply front and back traverses to a jack-spooler with means for operating them from the main shaft of the machine. The object of my present improvement is to provide a more simple and efficient attachment for all types of jack-spoolers arranged to operate the traverse-bars in such manner that while the rear traverse is relatively slow, the front traverse-bar is given a quick traverse. Through this improvement the yarn is laid on the spool with a cross-wind so that the individual ends build up in self-sustaining masses and therefore the yarn will deliver more freely and evenly in unwinding. In other words, the cross-winding of the yarn results in the coils being laid more evenly and uniformly and prevents them from becoming displaced or falling down over the ends of the mass so that they will deliver with a more uniform tension when the spool is unwound.

It will be seen that my improved device is particularly simple in construction and compact in arrangement while providing the maximum efficiency for the purpose described. The parts are few in number, easily attached to the machine, and in addition the brackets and clamps are adjustable to varying conditions so that they render the device universally applicable to practically all types of machines.

Various modifications might be made in the form and construction of the parts of my improved device without departing from the spirit or scope of the invention; therefore, without limiting myself to the exact embodiment shown and described, what I claim is:

1. In a traverse-mechanism for jack-spoolers, the combination with the driving-drum, drum-shaft and front and rear traverse-bars thereof, of a traverse-cam connected to be driven from the drum-shaft, a rockable traverse-lever adapted to be oscillated from the cam, adjustable means for connecting the lever to reciprocate the front traverse-bar with a quick traverse, a pawl on the traverse-lever, a ratchet-wheel adapted to be rotated from said pawl, an eccentric driven from the ratchet-wheel, and means attachable to the rear traverse-bar to engage the eccentric to traverse said bar with a relatively slow traverse.

2. In a traverse-mechanism for jack-spoolers, the combination with the reciprocatable front and rear traverse-bars thereof, of a clamp-member adjustably attachable to the front traverse-bar, a traverse-arm mounted on said clamp, a bracket attachable to the frame of the spooler, a lever pivoted on said bracket, means connecting the lever with the traverse-arm, a cam rotatably mounted on the bracket to oscillate the traverse-lever to reciprocate the traverse-bar, a shaft journaled in bearings on the frame of the spooler, a ratchet-wheel on said shaft, a pawl on the traverse-lever adapted to rotate the ratchet-wheel to turn its shaft, a resiliently-operated check-pawl engaging the teeth of the ratchet-wheel to prevent backward rotation thereof, an eccentric on the ratchet-wheel shaft, and a member attachable to the rear traverse-bar to be engaged by the eccentric to impart a relatively slow traverse to said bar.

3. In a traverse-mechanism for jack-spoolers, the combination with the front and rear traverse-bars thereof, of a bracket for attachment to the frame of the spooler, a traverse-lever pivoted on said bracket, means for adjustably connecting one arm of said lever with the front traverse-bar, a cam rotatably mounted on the bracket to oscillate the traverse-lever, a shaft supported in bearings on the spooler-frame, a

ratchet-wheel mounted on said shaft, a bracket adjacent said ratchet-wheel formed with a pocket, a plunger-pawl mounted in said pocket, a spring for maintaining the pawl in engagement with the teeth on the ratchet-wheel, a pawl on the traverse-lever for rotating the ratchet-wheel therefrom, an eccentric on the ratchet-wheel shaft, and means engaging said eccentric to impart reciprocation to the rear traverse-bar.

In testimony whereof I affix my signature in presence of two witnesses.

THOMAS H. NUTE.
